(57) **CLAIM**

The ornamental design for a reflex sight, as shown and described.

DESCRIPTION

FIG. 1 is a perspective view of a reflex sight;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines and the areas within them in FIGS. 1, 4 and 6 depict portions of the reflex sight that form no part of the claimed design.
